BUCKLE

Filed Feb. 5, 1926

UNITED STATES PATENT OFFICE.

HOWARD W. RUSSELL, OF COLLINGSWOOD, NEW JERSEY.

BUCKLE.

Application filed February 5, 1926. Serial No. 86,112.

This invention relates to a buckle, clasp or fastener which is adapted to connect the end of a strap with another object as for instance the side of a brief case or traveling bag or for connecting two ends of a belt.

It is the object of this invention to provide a buckle for this purpose which is comparatively simple and inexpensive in construction, which can be readily opened and permit of adjusting the strap lengthwise on the buckle, which is compact and neat in appearance and will reliably hold the strap in its adjusted position and which permits the strap to be adjusted readily up and down on the wall of the brief case and also instantly unbuttoned from this wall without disturbing the lengthwise adjustment of the buckle on the strap, thus permitting of instantaneous opening of the brief case without unbuckling the strap.

In the accompanying drawings:

Figure 1 is a fragmentary front view of a brief case showing my improved buckle applied to one of its straps and the front wall of the case.

Figure 2 is a vertical section taken on line 2—2, Fig. 1.

Figure 3 is a cross section taken on the correspondingly numbered line in Fig. 1.

Figure 4 is a front elevation showing my improved buckle utilized for connecting opposite ends of a strap so as to form a belt.

Figure 5 is a side elevation of the same.

Figure 6 is a fragmentary longitudinal section taken on line 6—6, Fig. 4 but showing the spring arm of the buckle unlocked from the adjusting pin.

Figure 7 is a longitudinal section similar to Fig. 2 but showing the buckle riveted to the front wall of a brief case or similar member.

Similar characters of reference indicate corresponding parts in the several views of the drawings.

Referring to the construction shown in Figs. 1, 2 and 3, the numeral 10 represents the front wall of a brief case, 11 the upper flap which closes downwardly against the front side of the wall 10, and 12 one of the fastening straps which is attached at its upper end to the flap 11 and adapted to be connected at its lower end with the front wall 10 by means of the buckle which embodies my invention. This strap is provided with a longitudinal row of openings

13 which are preferably arranged midway between the opposite edges of this strap.

In the construction shown in Figs. 1, 2 and 3 my improved buckle is organized in one form and associated with other parts so that it is capable of being moved vertically on the front wall of the brief case and the strap is also capable of being adjusted lengthwise on the buckle. In the form of the buckle as shown in Figs. 1, 2 and 3 the same comprises a base or plate 14 which is adapted to be engaged on its front side by the strap 12 and is provided midway between its longitudinal edges with a forwardly projecting adjusting pin 15 adapted to engage with one or another of the longitudinal row of openings 13 for the purpose of adjusting the position of this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

another of a longitudinal row of slots 18 formed in an adjusting plate 19 which is mounted on the front wall of the brief case and thereby permit of adjusting this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

another of a longitudinal row of slots 18 formed in an adjusting plate 19 which is mounted on the front wall of the brief case and thereby permit of adjusting this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

another of a longitudinal row of slots 18 formed in an adjusting plate 19 which is mounted on the front wall of the brief case and thereby permit of adjusting this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

another of a longitudinal row of slots 18 formed in an adjusting plate 19 which is mounted on the front wall of the brief case and thereby permit of adjusting this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

another of a longitudinal row of slots 18 formed in an adjusting plate 19 which is mounted on the front wall of the brief case and thereby permit of adjusting this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

another of a longitudinal row of slots 18 formed in an adjusting plate 19 which is mounted on the front wall of the brief case and thereby permit of adjusting this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

another of a longitudinal row of slots 18 formed in an adjusting plate 19 which is mounted on the front wall of the brief case and thereby permit of adjusting this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

another of a longitudinal row of slots 18 formed in an adjusting plate 19 which is mounted on the front wall of the brief case and thereby permit of adjusting this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

another of a longitudinal row of slots 18 formed in an adjusting plate 19 which is mounted on the front wall of the brief case and thereby permit of adjusting this buckle on the strap and adapting the capacity of the brief case to the volume of material which is to be stowed therein. On its rear side the base plate 14 is provided with a button having an elongated head 16 and a reduced neck 17 forming a T-shaped structure which is adapted to engage with one or

nal flanges projecting forwardly from opposite longitudinal edges of the base 14 and confining the strap 12 therebetween. Pivotally mounted on the flanges 22 and arranged between the upper parts thereof is a cam or eccentric 23 which is adapted to bear against the adjacent part of the strap upon engaging its highest part therewith and thereby clamp the strap against the base 14, while upon turning this cam so as to disengage the high part thereof from the strap the latter will be released and free to be moved lengthwise upon the buckle after the same has been detached from the adjusting pin 15. This cam is turned by means of an operating arm 24 which projects downwardly therefrom and is preferably constructed in the form of a thin, flexible sheet which is capable of springing. Near its lower end this operating arm is provided with an opening 25 which is adapted to receive the adjusting pin 15 upon swinging the arm downwardly over this pin in which the salient or high part of the cam or eccentric engages with the front side of the strap 12. In order to retain this arm and cam in this operative position the adjusting pin 15 is interlocked with this arm for which purpose this pin is provided on its upper side with a locking notch 26 which is adapted to be engaged by the upper edge portion of the opening 25 in the operating arm, as shown in Fig. 2, thereby yieldingly locking the cam in its clamped position. Upon lifting or moving the lower end of the arm 24 away from the strap, the upper edge of the opening 25 in this arm will be disengaged from the locking notch 26 on the pin 15 and this arm may be then wholly disengaged from this pin and the cam moved into a released position relative to the strap, after which the strap may be moved lengthwise of the buckle, and then re-engaging the locking pin with one or another of the openings 13 in order to adapt the relative position of the strap and buckle to suit requirements. While thus engaging the operating arm with the notch of the adjusting pin and disengaging the same therefrom this arm is sprung or flexed somewhat, this being possible due to the springy character of this arm which causes the operating arm to be yieldingly held in its locking position and still permits of easily opening as well as closing the buckle.

Additional means for holding the arm 24 in its locked or closed position may be provided such as the locking lips 27 arranged on the front edges of the flanges 22 transversely in line with the adjusting pin 15 and bent inwardly toward this pin and into the path of the longitudinal edges of the arm 24. Upon pressing the operating arm 24 inwardly or rearwardly over the adjusting pin 15 the opposite longitudinal edges of

this arm at the same time are sprung past the inner ends of the locking lips 27 and into a position underneath the same, as shown in Fig. 3, thereby serving to yieldingly hold this arm in its closed position. Upon pressing the operating arm 24 outwardly the opposite longitudinal edge portions of the same bend or yield slightly, which together with the resilient character of the locking lips 27 and the flanges which carry the same, permit this arm to be disengaged from these locking lips for opening the buckle preparatory to adjusting the strap thereon.

When it is desired to adjust the strap and buckle lengthwise one relatively to the other this is accomplished by simply pulling outward and upward on the free lower end of the strap which pull disengages the arm 24 from the locking lips 27 and the pin 15 and leaves the strap free from this pin and released from the cam and ready for instant readjustment by inserting the pin 15 in one of the holes 13 and again clamping the cam against the strap by simply pressing the arm 24 backwardly until it engages under the shoulder of the pin and underneath the lips, thus safely securing the strap until further adjustment or opening is desired.

By means of the cam or eccentric and the adjusting pin 15 the strap is reliably held against lengthwise movement on the buckle after the same has been closed, and by means of the interlocking engagement of the operating arm 24 with the adjusting pin 15 and the side flanges of the base this buckle is reliably held against accidental displacement and yet permits of easily opening and closing the buckle.

Obviously an upward pull of the strap on the buckle when the cam is in its closed position will cause the latter to grip with increasing fastness in proportion to the pull of the strap thereby insuring against slippage of the strap on the buckle in the event that there should be any wear in the holes of the strap which are in engagement with the adjusting pin 15.

Instead of mounting this buckle on the front wall of the brief case or bag so that the buckle itself is adjustable vertically thereon, this buckle may be permanently attached to this wall by securing the base of the buckle to this wall 10 by means of rivets 28, as shown in Fig. 7.

If desired this buckle may also be employed to advantage for connecting opposite ends of a strap 29 by mounting one end of this strap adjustably on the buckle in the manner in which this is done in Figs. 1, 2 and 3 while the other end of the strap is attached to a loop 30 arranged in the lower end of the base 14, as shown in Figs. 4, 5 and 6.

I claim as my invention:—
A buckle comprising a base adapted to be

mounted on a member and to engage with the rear side of a strap having a longitudinal row of openings, longitudinal flanges arranged on opposite edges of said base and having inwardly projecting detent lips, a pin arranged on the front side of said base and adapted to enter one or another of said openings and having a shoulder, a cam pivoted on said flanges, and a flexible arm ar-

ranged on said cam and adapted to engage 10 its opposite longitudinal edges with said lips and having an opening which receives said pin and the edge of which engages with said shoulder.

In testimony whereof I hereby affix my 15 signature.

HOWARD W. RUSSELL.
